UNITED STATES PATENT OFFICE.

FRANK D. HIGBEE, OF NEW YORK, N. Y., ASSIGNOR TO THE AMERICAN GOLD STATUE COMPANY, OF SAME PLACE.

DESIGN FOR A STATUE.

SPECIFICATION forming part of Design No. 32,474, dated April 10, 1900.

Application filed March 15, 1900. Serial No. 8,851. Term of patent 14 years.

To all whom it may concern:

Be it known that I, FRANK D. HIGBEE, a citizen of the United States, residing in the city, county, and State of New York, have invented 5 and produced a new and original Design for a Statue, of which the following is a specification, reference being had to the accompanying drawing, forming part thereof.

As shown in the drawing, my design is for 10 a statue representing a full-length female figure A, standing upon a base B, with the arms in a hanging position at either side of the body.

The leading or material features of my 15 design consist of the raised fluted plaits c, running in pairs lengthwise of the skirt d from the waist e to the bottom of the skirt d, and the fluted plaits f on the waist portion e, extending from the top of the skirt d to the yoke h and along the outside of each sleeve i of the 20 dress.

The yoke h is represented as of lacework and as extending from the top of the waist portion e up around the neck of the figure and forming a collar k.

The general configuration of the base B is 25 square, the lower sides l being plain, with a concave portion m between the top of such plain sides and the top of the base, the edges of the top of the base being rounded.

What I claim as new, and desire to secure 30 by Letters Patent, is—

The design for a statue as herein shown and described.

In testimony whereof I have signed my name to this specification in the presence of 35 two subscribing witnesses.

FRANK D. HIGBEE.
